UNITED STATES PATENT OFFICE.

HERMAN F. AMBOS, OF COLUMBUS, OHIO, ASSIGNOR TO THE COLUMBUS MACHINE COMPANY, OF SAME PLACE.

VALVE-GEAR.

SPECIFICATION forming part of Letters Patent No. 297,656, dated April 29, 1884.

Application filed January 7, 1884. (No model.)

To all whom it may concern:

Be it known that I, HERMAN F. AMBOS, a citizen of the United States, residing at Columbus, in the county of Franklin and State of Ohio, have invented a new and useful Valve-Gear, of which the following, in connection with the annexed drawings and letters of reference thereon, is a specification.

My invention relates to certain improvements in the mechanism by which the puppet-valve or other valves of a steam-engine are operated; and the objects of my invention are, first, to produce a very quick and sure movement for opening and closing such valve or valves; and, second, to make the said movement adjustable and adaptable for a variable cut-off, and thus operating the steam-engine with more or less expansion. I attain these objects by the mechanism illustrated in the accompanying drawings, in which—

Figure 1 is a view, partly in elevation and partly in section, of my invention as applied to steam-chests of puppet-valves. Fig. 2 is a detail view of the adjustable portion of my valve-motion. Fig. 3 is a central transverse section through the regulating or adjusting nut and screw of the same. Fig. 4 is a front elevation of the mechanism shown in Fig. 2. Fig. 5 is a top view of the mechanism shown in Fig. 1. Fig. 6 is a linear diagram of my invention, illustrating the position of the several main constituent parts of the mechanism when the main eccentric stands at its greatest altitude, which eccentric is not shown. Fig. 7 is a similar diagram answering to the middle position of the main eccentric. Fig. 8 is a similar diagram answering to the reversed position of the eccentric as seen in Fig. 6. Fig. 9 is a rear view of my valve-motion, the steam-chests, valves, and valve-rods being omitted.

A in the drawings represents a portion of the main frame of my machine, to which the whole mechanism is suitably attached. B represents a steam-chest containing the main valves. C represents the main shaft, and D D' D² eccentrics.

The steam-engine to which I have applied my invention being of ordinary construction, I have omitted in the drawings the steam-cylinder, exhaust-valves, piston, piston-rod, con-

necting-rod, and other parts not strictly necessary to illustrate the same.

The eccentric D is, by means of a longitudinally-adjustable eccentric-rod, d, connected with a horizontal shaft, E, which is hung between the swinging arms e, pivoted at e' to one of the steam-chests B, or to any suitable portion of the frame A. The shaft E is provided with a disk, e², to which, at two diametrically-opposite points, wrist-pins e³ e⁴ are fastened. A longitudinally-adjustable connecting-rod, f, connects the wrist-pin e³ with a pin, f', on a circularly-moving slide, f². The slide f² is fitted upon a curved arm, F, of a sleeve, f³, which is fitted to shaft G, hung by means of two brackets, g, to the frame A. This slide f² has a slotted head, f⁴, with a pin, f⁵, to which the cross-head f⁶ of a screw, f⁷, is pivoted. The sleeve f³ is provided with a slotted head, f⁸, to which a swiveled bearing, H, is hung by means of trunnions h, formed thereon. Through this bearing H a cylindrical nut, h', is passed, having a shoulder, h², on one side, and a burr or nut, h³, on the other side of the bearing, (see Fig. 2,) so as to prevent longitudinal displacement. This nut h' is fitted upon the screw f⁷, and is provided with a hand-wheel, h⁴, which, when turned, will move the screw f⁷ and the slide f² either one way or the other—that is, either backward or forward—thereby changing the position of the pin f'. The sleeve f³ is provided with a horizontal crank-arm, F', and wrist-pin f⁹, by means of which a longitudinally-adjustable eccentric-rod, d', is connected with the eccentric D'. A longitudinally-adjustable connecting-rod, I, connects the wrist-pin e⁴ of the disk E with the wrist-pin i of an arm, i', of a crank, I'. An arm, i², of the crank I' transfers its motion by means of a wrist-pin, i³, and a longitudinally-adjustable connecting-rod, I², to a crank-pin, k, on the upper arm, k', of a lever, K, which lever is suitably pivoted at k² to a steam-chest coupling, B', or to any suitable portion of the frame A. On the lower arm, k³, of the said lever K a wrist-pin, k⁴, is provided, which, by means of a longitudinally-adjustable connecting-rod, k⁵, is connected with a wrist-pin, l, of an arm, l', of a tappet-lever, L. The tappet-lever

L is pivoted at l^2 in a suitable manner to the steam-chest coupling B', and is provided with another arm, l^3 , having a tappet-head, l^4 , at its end. The outer extreme surface, l^5 , of the tappet-head is of circular form, and concentric with the fulcrum-pivot l^2 , for reasons hereinafter stated. The tappet-head l^4 moves in an oblong frame, m , of the valve-rod m' , to which the steam-valve or steam-valves M of one of the steam-chests B are attached. A similar tappet-lever, L', is provided for the right-hand steam-chest B; but as the motion of the valves here must be the reverse of the motion of the valves in the left-hand steam-chest, the longitudinally-adjustable connecting-rod I' connects the wrist-pins l and k , as seen in Fig. 1, and the lever L' stands in a position vertically opposite that of the lever L. Thus it will be seen that the valves M, operated by the levers L L', open and close at intervals, answering two diametrically opposite positions of the crank of the main shaft C or of the eccentrics D D' D''. As the levers L L' oscillate, the tappet-heads l move alternately in and out of the frames m of the valve-rods m' , and by moving into the frames they strike the inner surfaces of the same and open the valves with a very quick motion, which is due to the fact that the quickest-acting portion of the lever motion is made available for the operation of the valves, while the slowest-acting portion of the lever motion is not utilized for moving the valves, the tappet-heads l swinging outside of the frames m , and their surfaces l^5 bearing against the forward inner surfaces of said frames, and thus preventing the valves becoming incidentally moved.

By means of the mechanism interposed between the eccentrics D D' and lever K the motion of the eccentric-rods d d' is so modified that it becomes very rapid at the moment the valve is to be operated, inasmuch as then the wrist-pins e^3 e^4 occupy such positions which will afford the greatest leverage for rapid motion of the connecting-rods I and I', and thus I avoid the wire-drawing of steam when the valves begin to open.

When it is desired to cut off steam at an earlier stage than that at which the cutting off is found to take place, the slide f^2 is, by means of the hand-screw h^4 , as above stated, moved toward the end of the arm F, and the movement of the pin f' is thereby increased and the stroke of the connecting-rods I I' diminished, while the pin f' ascends or descends synchronously with the connecting-rod I, and

consequently the valves will be held open for a shorter period, and the steam-engine will work with more expansion. The reverse will be effected when the slide f^2 is moved toward the fulcrum of the arm F.

The eccentric D'', eccentric-rod d^2 , and lever N are parts of the exhaust-valve motion, and will be understood by those skilled in the art without further explanation.

It is readily seen that the above-described mechanism may be adopted for operating slide-valves or oscillating valves of flat or conical construction. It is also evident that the said mechanism may be made an automatic cut-off by suitably connecting the slide f^2 with the sliding collar of a pendulum or spring-weight governor.

What I claim as my invention, and desire to secure by Letters Patent, is—

1. In a valve-motion for steam-engines, the combination of a stroke-varying mechanism, comprising the adjustable slide and its connections, and a stroke-increasing mechanism, comprising the disk e^2 and its connections, whereby a very quick and variable or adjustable valve-stroke is obtained, substantially as and for the purpose described.

2. The combination of the eccentric-rod d , operating the center shaft, E, of the disk e^2 , the wrist-pins e^3 e^4 , connecting-rods f I, lever-arm i , having a wrist-pin, i , and swinging arm F, having pin f' , whereby a rapid motion for the valve is obtained, substantially as and for the purpose described.

3. The combination of the slide f^2 , the swinging arm F, having the adjusting device of the said slide attached to it, and the connecting-rods f and I, substantially as and for the purpose described.

4. The combination of the valves M, having frames m and valve-rods m' , and the operating-levers L L', having tappet-heads l^4 of the construction shown, whereby only the greatest speed of the valve-motion is utilized, substantially as and for the purpose described.

5. The combination of the valve-rods m' , having oblong frames m , and the tappet-levers L L', having concentric surfaces l^5 , whereby the valves M are kept in their closed position, substantially as and for the purpose described.

HERMAN F. AMBOS.
